UNITED STATES PATENT OFFICE

2,005,155

TUBE EXPANDING MILL

Bolton C. Moise, Pittsburgh, Pa.

Application February 23, 1932, Serial No. 594,621

1 Claim. (Cl. 80—13)

My invention relates to seamless pipe and tube mills, and particularly to expanding and rolling mills. In these mills a set of rolls draws rough pierced shells over a mandrel supported on a long 5 rod. When the shells first pass over the mandrel and begin to travel forward over this rod, it is possible to use rod supports. These supports must soon be withdrawn, however, to permit the tube's 10 travel over the major portion of the rod, leaving the latter quite unsupported and free to whip so that it cannot hold the mandrel in the tube center of the shells. In addition, the rolls slip to a certain extent on the shells, which slows up the production of the mill.

One of my objects is to construct a mill in a manner that substantially eliminates the above objectionable features. Other objects may later become apparent from the following disclosure.

Briefly, my invention consists in constructing 20 the mandrel of a tube mill with a bearing surface, and providing a ram having a bearing surface that may coact with that of the mandrel and arranged to push rough shells over the latter. A set of rolls are positioned on either side of this mandrel 25 in the ordinary manner and the rest of the mill is generally conventional.

As the ram pushes a shell through these rolls and over this mandrel, the latter may be supported or steadied by the ram through the medium of 30 the pair's coacting bearing surfaces. In addition, the ram may be run at a speed that relieves the rolls of the burden of moving the shells, thus practically eliminating any roll slippage.

A specific example of a seamless tube mill constructed according to my invention is illustrated 35 by the accompanying drawings, Figure 1 being a cross-sectioned side elevation and Figure 2 a partially cross-sectioned plan.

This mill includes a pair of rolls 1 arranged on 40 either side of a mandrel 2 carried by a thrust bar 3. These rolls are the conventional axially in-

clined disk rolls that both shape and draw the shells over the mandrel.

In the present instance, these rolls are relieved, or at least partially relieved, of the burden of longitudinally moving the shells, by a ram 4 mounted in a thrust bearing 5 carried by a slide 6 which is moved by a cable and drum arrangement 7 driven by a motor 8. This motor may be operated continuously to first forcibly start the shells and then drive them completely over 10 the mandrel 2.

The bearing surfaces for the mandrel and ram consist of a rod extension 9 carried by the former and a bore 10 formed in the latter. As the ram pushes the last portion of a shell over the mandrel this extension enters the bore so that the ram acts as a steadyng agency. The ram is then run back to permit the entrance of another shell into the mill.

Although I have shown a specific form of my invention in accordance with the patent statutes, I do not intend to limit its scope thereto, except as defined by the following claim.

I claim:

A tube rolling mill including the combination of a set of working rolls constructed and arranged to continuously engage the work during each rolling operation, a mandrel, means for continuously holding said mandrel at a predetermined position 30 between said rolls, a ram for engaging the rear end of said work, means for mounting said ram for continuous movement for a distance at least equaling the length of said work and means for applying continuous force directed towards said 35 mandrel to said ram during the rolling operation of said mill, said mandrel and ram having coacting portions that are constructed and arranged to positively interengage when said ram approaches said mandrel.

BOLTON C. MOISE.
